UNITED STATES PATENT OFFICE.

WILBUR L. HOUSEMAN, OF PHILADELPHIA, PENNSYLVANIA, ASSIGNOR TO STAND-
ARD MACHINE COMPANY, OF PHILADELPHIA, PENNSYLVANIA, A CORPORATION
OF PENNSYLVANIA.

CIRCULAR-KNITTING MACHINE.

Application filed May 3, 1922. Serial No. 558,147.

To all whom it may concern:

Be it known that I, WILBUR L. HOUSEMAN, a citizen of the United States, residing at Philadelphia, county of Philadelphia, and 5
5 State of Pennsylvania, have invented a new and useful Improvement in Circular-Knitting Machines, of which the following is a full, clear, and exact description, reference being had to the accompanying drawings, 10
10 which form a part of this specification.

In the manufacture of hosiery it is well known to provide a plurality of yarn carriers or guides from which threads of different character are led to the needle cylinder, 15 and which are movable into and out of position to cause them to be caught by the hooks of the needles, so that any one or more of them may be, at any given time, directed to, or withdrawn from, the needles, thereby 20 causing the character of the knitted fabric to be different at different points in the length of the stocking. As an example, threads of different colors may be provided so as to produce a stocking one or more 25 parts of which are of one color and one or more parts of another color. Another and more specific example is where the heel and toe, and particularly the tip portions of the heel and toe, are knit from yarn of a color 30 different from that of the remainder of the stocking.

In changing yarn, it is customary to cause the yarn that is moved out of knitting relation with the needles to be clamped at a 35 point between the last needle on which it is knit and the yarn guide and then to cut the yarn between the clamp and the last needle on which it is knit. This leaves a free end 40 of yarn extending from such last needle, loosely within the circle of needles. It also leaves a clamped end of yarn extending from the yarn guide. When this yarn is again moved into knitting relation with the needles, the clamped end of yarn is released, 45 and again a free end of yarn, extending from the first needle on which the yarn is knit, is left extending loosely within the circle of needles. Bearing in mind, therefore, that as one yarn is moved in to knit, the 50 other yarn is moved out, it will be understood that, at the time of yarn change, there are two floating ends of yarn. Either of these floating ends is likely to be caught by the needles and knitted in with the other

threads, thereby, especially in the case of a 55 differently colored thread, so marring the stocking that it is not of first quality and is salable only at a reduced price.

The object of the present invention is to provide new and improved means for guiding and holding these free or floating ends of severed yarn away from the needles so that they cannot be accidentally caught thereby and knitted into the fabric. The invention is more particularly applicable to machines arranged to exchange threads during oscillation of the needle cylinder, as in the knitting of the heel or toe. I am aware that this object has been heretofore sought and achieved, but I believe the structure I 60 have devised presents decided advantages in simplicity of construction and mode of operation and particularly in that the object sought is secured by means wholly mechanical and positive. 65

In the drawings, which show a preferred embodiment of my invention:

Fig. 1 is a plan view of the top of the knitting machine comprising principally the needles, the yarn guides, the clamp and cutter and their actuating mechanism, and the mechanism for guiding and holding the loose end of yarn out of knitting relation with the needles. 75

Fig. 2 is a side view of the mechanism of 80 Fig. 1, the needle cylinder being shown in vertical section.

Fig. 3 is a side view of the clamp, looking 85 toward the left, Fig. 1.

Fig. 4 is a side view of the cutter, looking 90 toward the right, Fig. 1.

Figs. 5, 6 and 7 are diagrams showing the mode of operation of my invention.

Fig. 8 is a side view of the device which directly engages the free end of severed 95 yarn and moves and holds it into position to prevent accidental engagement with the needles.

The needle cylinder *a* carries the independent needles *b* actuated by cams (not 100 shown).

Secured to the yarn bracket *c* is a bar *d* carrying a block *e* forming a support for the clamp and cutter. Projecting in front of the block *e* is a fixed yarn-engaging foot *f*. 105 To the bottoms of block *e* and foot *f* is secured a plate *g* which extends over the larger part of the area enclosed by the

needles. This plate is more fully described hereinafter.

Pivoted between its ends to one side of the block *e* is a clamping jaw *h*. A spring *i* tends to hold the jaw against the plate *g* and in that position to clamp yarn that has been drawn from a yarn guide over the plate in the rotation of the needles. The spring *i* connects one free end of the clamping jaw *h* with the free end of an arm *j* which is held in fixed position by means of a set screw *k*. The tension of this spring may be readily adjusted by loosening the screw *k* and turning the arm *j* into position to impose the desired tension on the spring *i* and by then tightening the set screw to hold the arm in its adjusted position.

Secured to the other side of the block *e* is the fixed blade *m* of a cutter. Pivoted to the same side of the block is the movable blade *n* of the cutter. This blade is actuated by a spring *o* when allowed to act by the control mechanism for the clamp and cutter.

This control mechanism comprises a lever *p* pivoted at one end to the machine frame and at the other end carrying a lifter *r* having side projections *r'* and *r''* adapted to extend, respectively, under projection *h'* of the clamping jaw *h* and projection *n'* of cutter blade *n*.

q is a yielding clamp which is associated with the positively operating clamp *h*, but it plays no necessary part in the operation of the present invention.

w, *y* and *z* represent yarn guides.

At the time of yarn change, when it is desired that the clamp and cutter shall act, the lever *p* is lifted by means of a vertically movable rod *s* (operable automatically), which engages a set screw *t* on the lever *p*. Thereby the cutter blade *n* and the clamping jaw *h* are successively lifted. At this time the inactive end of yarn that has been previously held by the clamp is moved down by its yarn guide into operative relation with the hooks of the needles and the clamped end is released. The other yarn, which it is desired to move out of action, is lifted by its yarn guides out of operative relation with the needles and the end extending therefrom to the fabric is drawn, by the rotation of the needle cylinder, under the clamping jaw *h*, in front of the foot *f*, over the fixed cutter blade *m* and under the movable cutter blade *n*. Successive positions of a yarn about to be cut and clamped are indicated by the dotted lines 11, 12, 13 and 14 in Figs. 5 and 6. When such yarn has about reached the position shown at 14, the rod *s* is dropped by the pattern mechanism and the lever *p* falls into the position shown in Fig. 2, first releasing the clamping jaw *h* and allowing its spring *i* to move it into clamping position and then releasing the

cutting blade *n* and allowing its spring *o* to actuate it to sever the thread.

I have heretofore referred to the plate *g*, which acts as a floor over which the yarn is drawn and as an element which cooperates with the clamping jaw *h*. The cutter *m*, *n* is located just beyond the edge of the plate, which extends across the circular space within the needles except for an open segmental space adjacent the cutter. At one side of this segmental space, the plate has an arcuate extension *u* having a reduced extremity *v*, acting as a deflector, as hereinafter described, the point of which lies close to the needles. Adjacent the root of this deflector is an upright post *w*. The lower face of the deflector is bevelled, as shown in Fig. 8.

When the yarn that has been rendered inactive reaches the position 13, Fig. 5, before cutting and clamping, it contacts with the post *w*, about which it is drawn as the needle cylinder continues to rotate in the direction shown by the arrows in Figs. 5 and 6. After this yarn has been cut and has been carried beyond the position 14 shown in Fig. 6, the needle cylinder reverses its direction of rotation, as in the knitting of heel and toe, and the end of yarn is carried under the deflector and thus under the plate *g*, at which level it is held. At this level it cannot accidentally engage the hooks of the needles.

After the yarn reaches the position shown in Fig. 6 at 14 and is cut and clamped as described, a confined end of yarn extends from the yarn guide *y* to the clamp and beyond, as shown at 15, Fig. 7. When the yarn guide *y* is again moved into operative position and the clamp *h* retracted, this end of yarn is released and becomes a floating end, which is even longer than that floating end formed when the same yarn was moved out of operative position (as previously described) and is likely to give more trouble. Successive positions of this yarn, as the needle cylinder continues to rotate, are shown at 16, 17 and 18. After the yarn has been carried beyond position 18, the needle cylinder is reversed and the loose end of yarn is carried under the deflector and thus under the plate *g*, at which level it is held.

The post *w*, although of advantage, is not absolutely essential; but without the deflector the end of yarn would remain above the plate *g* and would be likely to move outward and fall between some of the needles and thus be knit into the fabric.

For the sake of clearness, I have illustrated, in Figs. 5, 6 and 7, but one yarn. The yarns from all the carriers are, however, cut, clamped and deflected under the plate *g* in the same way; and the free ends are taken care of in the same way, whether it is the free end formed after throwing the yarn out of operation, as shown in Figs. 5

and 6, or the end that is released after throwing the yarn into operation, as shown in Fig. 7.

It will, therefore, be understood that at every change of yarn, two floating ends are formed, one by the yarn that has just been engaged with the needles and the other by the yarn that has just been disengaged therefrom, and that both floating ends are taken care of in the same way so as to eliminate all danger of their accidental engagement with the needles.

Having now fully described my invention, what I claim and desire to protect by Letters Patent is:

1. The combination with an oscillatable needle cylinder, a plurality of yarn guides, a clamp and a cutter, of a deflector so positioned that that portion of the floating end of cut yarn which is adjacent the fabric is carried, in the travel of the needle cylinder in one direction, beyond the deflector, the said deflector being adapted to engage said floating end in the reverse travel of the needle cylinder and draw it out of position to accidentally engage with the needles.

2. The combination with an oscillatable needle cylinder, a plurality of yarn guides, a clamp and a cutter, of means to operate the clamp and cutter in the travel of the cylinder in one direction, and means operative in the travel of the cylinder in the opposite direction adapted to engage an end of yarn extending from the moving knitted fabric and deflect the severed loose end out of position permitting accidental engagement with the needles.

3. The combination with an oscillatable needle cylinder, a plurality of yarn guides, a clamp and a cutter, of a deflector adapted to deflect a severed end of yarn floating from the moving knitted fabric, said deflector being so positioned that that portion of the floating end of severed yarn which is adjacent the fabric is carried, in the rotation of the needle cylinder in one direction, beyond the deflector and is engaged thereby in the reverse travel of the needle cylinder, and means to hold the so-deflected floating end of yarn out of position permitting accidental engagement with the needles.

4. The combination with a rotatable needle cylinder, a plurality of yarn guides, a clamp and a cutter, of a plate underlying the clamping jaw and extending over a large part of the area enclosed by the circle of needles, and a deflector projecting beyond the plate adapted, in the rotation of the needles, to engage a floating end of yarn and deflect the end thereof under the plate, where it will be held out of position to accidentally engage the needles.

5. The combination with a rotatable needle cylinder, a plurality of yarn guides, a clamp, a plate underlying the clamping jaw,

an arcuate extension from the plate, a deflector on said extension adjacent the needle bed, and a cutter extending over the space between the body of the plate and its arcuate extension.

6. The combination with a rotatable needle cylinder, a plurality of yarn guides, a clamp and a cutter, of a plate underlying the clamping jaw, an arcuate extension from the plate adjacent the cutter, and a deflector on said extension adjacent the needle bed, said deflector having an inner wall sloping at an acute angle toward the needle bed.

7. The combination with a rotatable needle cylinder, a plurality of yarn guides, a clamp and a cutter, of a post positioned between the cutter and the needle bed and adapted to engage an end of yarn that is formed at the time the yarn is cut when thrown out of action and about which such end is carried in the travel of the needles, and a deflector adapted to engage the yarn in the travel of the needles in the reverse direction and move the end of yarn out of position to prevent accidental engagement with the needles.

8. The combination with a rotatable needle cylinder, a plurality of yarn guides, a clamping jaw and a cutter, of a plate underlying the clamping jaw and extending over a large part of the area enclosed by the circle of needles, a post projecting above said plate between the cutter and the needle bed and adapted to engage an end of yarn that is formed at the time the yarn is cut when thrown out of action and about which such end is carried in the rotation of the needles in one direction, and a deflector projecting beyond said plate adapted, in the rotation of the needles in the opposite direction, to engage said yarn and deflect the end of yarn under the plate, where it will be held out of position to accidentally engage the needles.

9. The combination with a rotatable needle cylinder, a plurality of yarn guides, a clamping jaw and a cutter, of a plate adapted to hold a floating cut end of yarn out of engagement with the needles, an arcuate extension from the plate adjacent the cutter, a yarn-engaging post carried by said extension, and a deflector on said extension between the post and the needle bed and adapted to move the yarn into position to be held by the plate as specified.

10. The combination with a rotatable needle cylinder, a plurality of yarn guides, a clamping jaw and a cutter, of a plate underlying the clamping jaw, an arcuate extension from the plate adjacent the cutter, a post carried by said extension between the post and the needle bed, said deflector having an inner wall sloping from adjacent said post toward the needles.

11. The combination with a rotatable needle cylinder, a plurality of yarn guides, a clamping jaw and a cutter, of a plate underlying the clamping jaw, means to engage the yarn and cause it to travel as a chord of gradually increasing length as the needles travel in one direction, and means to engage the yarn on the return travel of the needles and deflect it under said plate.
- 10 12. The combination with a rotatable needle cylinder, a plurality of yarn guides, a clamp and a cutter, of means over which is carried the yarn which extends between a yarn guide and the fabric after said yarn 15 is disengaged from the needles preparatory

to clamping and cutting and also the yarn which extends from the fabric after the clamped end of yarn is re-engaged with the needles preparatory to unclamping, and a deflector adapted to engage the end of yarn which in either case floats from the fabric and draw said end under said means, said means thereafter acting to hold said loose ends from accidental engagement with the needles.

In testimony of which invention, I have hereunto set my hand, at Philadelphia, Pa., on this 27th day of April, 1922.

WILBUR L. HOUSEMAN.
